HAIR CURLER

Harry H. Klein, New York, N. Y.

Application August 31, 1933, Serial No. 687,590

13 Claims. (Cl. 132—41)

This invention relates to hair curlers, and particularly to the type wherein two or more arms or blades are hinged to each other and the hair is curled around and between the blades.

5 The principal object of the invention is to provide a conveniently utilizable, efficient, and improved hair curling device of the above type.

Another object is to provide a hair curler of the above type, the arms of which, although normally 10 pressing against each other under resilient tension, may be set to remain in an open inoperative condition.

Other objects and advantages will hereinafter appear.

15 In the accompanying drawings,—

Fig. 1 is a cross-sectional elevation of the hair curler.

Fig. 2 is a bottom plan view of the hair curler shown in Fig. 1.

20 Fig. 3 is an elevation showing a modification of the invention, as the hair curler appears while in operative condition.

Fig. 4 is a cross-sectional elevation of a portion 25 of a hair curler, which is another modification of the invention.

Figs. 5, 6 are cross-sectional views showing a detail of the hair curler.

Figs. 7, 8, 9 show other modifications of the invention.

30 The hair curler 1, Fig. 1, has a tubular bar 2, one terminal 3 of which is closed and compressed to constitute a hub 4 of reduced diameter, and its opposite terminal 5, Fig. 2, is formed into a pair of ears 6. An axle 7 passes through said ears, and is joined thereto by being formed into heads 8 located against each of the ears. On top of and against the bar 2 is located an arm 9, the end 10 of which is provided with a pair of ears

35 11 that are pivoted about the axle 7 and are positioned against the opposing sides of the ears 6. Over the arm 9 is stretched an elastic band 12, Fig. 3, having its terminals formed as collars 13, 14. One end of said band passes through an opening 15 of the arm 9, and its collar 13 is pivoted about the axle 7 between the arm-ears 11, and the collar 14 slips over the hub 4, as illustrated in Fig. 1. The ears 11 are configurated as a casing 16, Fig. 2, which completely conceals the collar 13 and the manner in which the same

40 with the end of the band 12 are joined and hinged to the axle 7. Within the tubular bar 2 is located a helical spring 17, one end of which bears against the closed terminal of said bar and in its opposite end is seated a detent 18 which

45 constantly presses against the casing 16. As the

joint axis of the tubular bar 2, spring 17, and detent 18 is lower than the transverse axis of axle 7, Fig. 1, and the casing 16 is of cam-like configuration, the arm 9 will normally be impelled to bear pressingly against the bar 2 as shown, but when said arm is swung about the axle 7 to the position shown by the dot and dash lines the detent 18 will press against the casing 16 to retain the arm under tension in the latter or inoperative position. A thumb-piece 19 is 10 preferably provided for the arm 9 to aid in opening and closing it to any desired position relatively to the bar 2.

According to the modification shown in Fig. 3, 15 the ears 6, 11 of the bar 2 and arm 9 respectively, are provided with angularly disposed opposing finger-pieces 20, 21, and the casing 16a is of square-like configuration, whereby abutment of said finger-pieces when pressed toward each other will limit the opening swinging movement 20 of the arm 9 to about the position shown by the dash and dot lines, the detent 18 in the latter position pressing against the side 16b of the casing and retaining it in the open position.

When utilizing either of the hair curlers of 25 Fig. 1 or Fig. 3, the arm 9 is first disposed to the open inoperative position, the hair is then retained around the bar 2, then the arm is closed to the spring-pressed position against the retained hair and bar 2, then the curling of the 30 hair is continued about the closed arm and bar, and then the elastic band 12 is stretched over the curled hair and its collar 14 is slipped over the hub 4, as shown in Fig. 3. The device is then left upon the hair in this condition for a requisite length of time, and it may be then removed by opening up its above parts and uncurling the hair therefrom.

In the modification shown in Fig. 4, the ears 11 of arm 9 are made plain as shown, without creating a casing 16, and the cam-acting function of the latter is instead performed by a collar 13a of the elastic band 12, which collar is configurated similarly to the casing 16. The detent 18 thus presses directly upon the collar 13a to maintain the arm 9 either in closed state under tension against the bar 2, or to positively retain said arm in an open or inoperative state.

The collar 13, 14, or 13a is preferably made by 45 providing a metallic ringed casing 22, Figs. 5, 6, which grips the terminal of the elastic band 12, and the latter is inserted and retained therein by passing through an opening 23 thereof and curling around its internal ringed bore 24.

50 It will be evident to those versed in the art 55

that with this hair curler and the above described improvements, many important advantages may be obtained, and efficient hair curling or hair waving may be accomplished with ease, convenience, and rapidity.

According to the modification shown in Fig. 7, the arm 9 is held under resilient tension against the bar 2, by means of a leaf spring 25 which is configurated to pass around the collar 13, and the arms 25a of which press away from each other and against the interior surfaces of the finger-pieces 26, 27, said spring being retained against possible outward displacement by the collar 13 and secured against possible inward displacement by the wall 2a of the bar 2. The finger-piece 26 is provided with a springy terminal 28, which is so configurated that when the two finger-pieces are pressed against each other the said terminal engages the extremity of finger-piece 27, as shown by the dash and dot lines, and thereby retains the arm 9 in the open inoperative state shown. Upon swinging of the arm 9 toward the bar 2, the finger-pieces 26, 27 uncatch and become disengaged from each other.

In the modification shown in Fig. 8 the arm 9 and bar 2 are pressed toward each other by means of a helical spring 29, which is secured to each of them in the location and manner shown and continually draws them against each other. In Fig. 9 a helical compression spring 30 has its terminals seated within pockets 31 formed in the finger-pieces 26, 27, and by continually pressing the finger-pieces away from each other causes the arm 9 and bar 2 to be maintained under resilient tension against each other.

Variations may be resorted to within the scope of the invention, and portions of the improvements may be used without others.

Having thus described my invention, I claim:—

1. A hair curler having the combination of a hair winding bar having a pair of ears, an axle passing through and joining said ears, a hair gripping arm having a pair of ears pivoted on said axle, and a hair gripping band being pivoted on said axle.
2. A hair curler having the combination of a hair winding bar having a pair of ears, an axle passing through and joining said ears, a hair gripping arm having a pair of ears pivoted on said axle, and a hair gripping band being pivoted on said axle and passing through an opening formed in said arm.
3. A hair curler having the combination of a hair winding bar having a pair of ears, an axle passing through and joining said ears, a hair gripping arm having a pair of ears pivoted on said axle, a hair gripping band having at its terminal a rigid collar, and said collar being pivoted on said axle.
4. A hair curler having the combination of a hair winding bar having a pair of ears, an axle passing through and joining said ears, a hair gripping arm having a pair of ears pivoted on said axle, a hair gripping band having at its terminal a rigid collar, said collar being pivoted on said axle, and said band passing through an opening formed in said arm.
5. A hair curler having the combination of a hair winding bar, an elastic hair gripping band therefor, a rigid hollow collar at the terminal of

said band, and said terminal being secured to said collar by entering an opening thereof and being twisted into its interior.

6. A hair curler having the combination of a hair winding bar, a hair gripping arm hinged thereto, each of said bar and arm having a finger-piece for their simultaneous manipulation, and a spring passing around the hinge having arms pressing said finger-pieces away from each other to cause said gripping arm and bar to bear resiliently against each other. 5

7. A hair curler having the combination of a hair winding bar, a hair gripping arm hinged thereto, each of said bar and arm having a finger-piece for their simultaneous manipulation, a 15 spring passing around the hinge having arms pressing said finger-pieces away from each other to cause said gripping arm and bar to bear resiliently against each other, and means to maintain said gripping arm away from said bar contrary to the action of said spring. 20

8. A hair curler having the combination of a hair winding bar, a hair gripping arm hinged thereto, each of said bar and arm having a finger-piece for their simultaneous manipulation, a 25 spring passing around the hinge having arms pressing said finger-pieces away from each other to cause said gripping arm and bar to bear resiliently against each other, and said finger-pieces having means to engage each other upon their 30 manipulation to maintain said gripping arm away from said bar contrary to the action of said spring.

9. A hair curler having the combination of a hair winding bar, a hair gripping arm hinged 35 thereto, said bar and arm each having a finger-piece for their simultaneous manipulation, a spring normally compelling said arm to bear resiliently against said bar, and said finger-pieces having means to engage each other upon their 40 manipulation to maintain said arm away from said bar contrary to the action of said spring.

10. A hair curler having the combination of a hair winding bar, a hair gripping arm hinged thereto, said bar and arm each having a finger-piece for their simultaneous manipulation, and a 45 helical spring secured to said bar and arm drawing them to each other.

11. A hair curler having the combination of a hair winding bar, a hair gripping arm hinged 50 thereto, said bar and arm each having a finger-piece for their simultaneous manipulation, and a helical spring pressing said finger-pieces away from each other to cause said arm and bar to bear against each other. 55

12. A hair curler having the combination of a hair winding bar, a hair gripping arm hinged thereto, a spring normally compelling said arm and bar to bear resiliently against each other, and said arm and bar having means to engage each other upon their opening manipulation to maintain them away from each other contrary to the action of said spring. 60

13. A hair curler having the combination of a hair winding bar having a pair of ears, an axle 65 passing through said ears, a hair gripping arm having a pair of ears pivoted on said axle, a hair gripping band having at its terminal a collar, and said collar being pivoted on said axle.
